CATHODE RAY TUBE

Max Knoll and Fritz Schröter, Berlin, Germany,
assignors to Telefunken Gesellschaft für
Drahtlose Telegraphie m. b. H., Berlin, Ger-
many, a corporation of Germany

Application August 4, 1934, Serial No. 738,434
In Germany August 2, 1933

6 Claims. (Cl. 250—27)

The invention is concerned with a Braun tube which is adapted to the reception of television pictures. It has been suggested to use for this purpose the same Braun tubes with a gas atmosphere that are employed for oscillographic work. A gas atmosphere acts against divergence of the cathode-ray pencil and thus creates a sharply outlined spot upon the screen of the tube. However, tubes of this kind involve the drawback that the size of the spot upon the screen of the tube is a function both of the gas pressure as well as the current strength in the cathode-ray pencil. Now, inasmuch as the strength of current in the cathode-ray pencil, with a view to changing the brightness of the spot on the screen must be varied along a line in the picture, sharp picture re-creation, strictly speaking, is feasible only in the presence of a particular value of brightness, whereas at other brightness values the spot would assume a larger diameter so that no sharp picture could be re-created.

The said shortcoming could be lessened by that gas pressure and maximum strength of current flowing in the cathode-ray pencil are so tuned or adjusted to each other that for the largest or nearly the largest current of the pencil the luminous spot will be of the smallest diameter. While the increase in the diameter of the spot, to be sure, will happen also in that case in an undiminished degree, it will not even to a remote extent make itself so disagreeably felt as before.

Another means to obviate the said drawback inherent in gas-filled television receiver tubes consists in that a magnetic or an electrically acting focussing device is used in addition to a gaseous atmosphere having a focussing effect also. This insures the advantage that the said increase in the diameter of the spot is lessened inasmuch as the ray-focussing action which is due to the magnetic or electric focussing means is independent of the strength of the pencil current.

The dependence upon the current strength of the cathode-ray pencil of the diameter of the spot can be nearly entirely caused to disappear if the focussing device is controlled at the rhythm or rate of the brightness modulation of the spot. This shall be explained in what follows by reference to Figs. 1, 2 and 3 of the drawing which refers to three different embodiments of the invention.

In Fig. 1 is illustrated a Braun tube with cathode 10, control cylinder 11, anode 12, deflector plate pairs 13, 14, and a magnetically acting focussing device, i. e., a focussing coil 15. Between the control cylinder 11 and the cathode 10 is

applied the potential serving for brightness modulation of the spot which is indicated in the drawing by a symbol indicating A. C. between the leads of cathode and control cylinder. The said focussing coil 15 is traversed by a D. C. and by an A. C. being in synchronism with the brightness modulation, a fact which is indicated in Fig. 1 by a D. C. and an A. C. symbol between the leads brought to the focussing coil. Suppose that the gas pressure and the current flowing through the focussing coil have been so chosen that in the presence of maximum pencil current the spot has the desired minimum diameter. If the voltage at the control cylinder changes in the sense of decreased luminosity, the current of the cathode-ray pencil will experience a decrease, while the diameter of the spot at the same time will grow. The current of the focussing coil will then increase in order that the small spot diameter occurring in the presence of maximum pencil current may be obtained.

Fig. 2 shows a Braun tube which, contradistinct to that shown in Fig. 1 is furnished with electric focussing means. The latter comprises three electrodes 16—18, the central one presenting a positive potential in reference to the two outer ones. The equipotential surfaces of the electrical field generated by the electrode potentials have a shape as roughly shown in Fig. 2 by dotted lines. These equipotential surfaces act upon the pencil of cathode-rays in the same focussing way as an optical lens of the biconvex type acts upon a pencil of light-rays. The potential difference between the central electrode and the outer ones, as explained in connection with Fig. 1, must grow whenever the brightness of the spot decreases.

It must also be mentioned that at the middle electrode 17 may be applied a potential that is positive in relation to the outer electrodes 16 and 18. This arrangement has also a focussing effect upon the cathode-rays. Also in this instance the potential difference must grow upon a reduction of the brightness of the spot.

A particularly simple embodiment of the invention is illustrated in Fig. 3 in which only the middle portion of the tube is depicted. The electrodes of the electric focussing device are to be disposed outside the glass wall of the tube and they consist here of annuli 19—21. The arrangement of the focussing electrodes without the tube, contradistinct from what is true of high-vacuum tubes, is feasible in the case of gas-filled tubes because in these no, or no appreciable, wall charges are able to form.

The electrodes could also be fitted directly upon the outside wall of the tube. Electrodes of this kind are manufactured particularly easily because the outside wall of the tube is sprayed with a metal, preferably with zinc.

We claim:

1. The method of producing luminous effects in electronic tubes which comprises applying electrical energy to a control electrode within the tube to vary thereby the brilliance of the luminous effects being produced, and electrically compensating for variances in the size of the luminous areas resulting in accordance with the applied electrical energy.
- 15 2. The method of maintaining constant size luminous spots in gas filled cathode ray tubes having a fluorescent end-wall, which comprises applying to a control electrode system within the tube signalling impulses tending to vary the brilliance of the luminous effects resulting from impact to the cathode ray beam upon the fluorescent end wall of the tube, and electrically compensating for variances in the size of the resulting luminous spot in accordance with the signalling impulses.
- 25 3. An electronic tube of the gas filled type comprising a fluorescent viewing screen, a source of electrons for developing under the application of suitable voltages a cathode ray beam, means for controlling the intensity of the cathode ray beam produced, means for supplying signalling impulses to said controlling means, and means energized in accordance with said signalling impulses for compensating for variances in the area of the resulting luminous spot produced by the impingement of the cathode ray beam upon the viewing screen.
- 30 4. In an electronic device of the cathode ray type having contained therein a gas, a source of electrons from which a cathode ray beam is de-

veloped, a fluorescent area at the end of the device opposite the electron source, means to control the resulting cathode ray beam developed within the tube so as to vary thereby the brilliance of the fluorescent effects produced upon the fluorescent area upon impact to the cathode ray, means for supplying signalling impulses to the control means energized by said signalling impulses to compensate for variances in area of the luminous effects produced.

5 5. In an electronic device of the cathode ray type having contained therein a gas, a source of electrons from which a cathode ray beam is developed, a fluorescent area at the end of the device 15 opposite the electron source, means to control the resulting cathode ray beam developed within the tube so as to vary thereby the brilliance of the fluorescent effects produced upon the fluorescent area upon impact to the cathode ray, means 20 for supplying signalling impulses to the control means and electrostatic means energized by said signalling impulses to compensate for variances in area of the luminous effects produced.

6. In an electronic device of the cathode ray 25 type having contained therein a gas, a source of electrons from which a cathode ray beam is developed, a fluorescent area at the end of the device opposite the electron source, means to control the resulting cathode ray beam developed within 30 the tube so as to vary thereby the brilliance of the fluorescent effects produced upon the fluorescent area upon impact to the cathode ray, means 35 to supply signalling impulses to the control means and a plurality of adjustable conducting ring members energized by the signalling impulses to compensate for variances in area of the luminous effects produced.
